HAIG ANTRANIKIAN, OF PARIS, FRANCE, ASSIGNOR OF ONE-HALF TO FRANKLIN T. MILLER, OF NEWTON, MASSACHUSETTS

RADIOGONIOMETER

Application filed August 14, 1928, Serial No. 299,606, and in France August 16, 1927.

The present invention, though having also more general fields of utility, is more particularly related to radiogoniometry.

A chief object of the present invention is to provide a new and improved radiogoniometer that shall be accurate, simple in construction, and efficient in operation.

With the above end in view, a feature of the invention resides in a preferred radiogoniometric receiving device having two crossed loop or coil aerials for receiving the signals, fixed to the plane or other apparatus with which the radiogoniometer is intended to be used. The loop aerials are connected in series with a common tuning condenser, and means is provided for periodically reversing the connections of one of the loop aerials. A further feature resides in a preferred transformer, one of the windings of which, say the primary winding, is constituted of crossed parts or bobbins, the angle between which is the same as the angle between the crossed loops, the connections of one of the bobbins being periodically reversed synchronously with the reversal of the loop aerials. The other winding of the preferred transformer,—say the secondary winding,—is preferably provided with two parallel bobbins, though it may be constituted of but a single bobbin. As will be explained hereinafter, the reversal may be effected in the parallel bobbins instead of in the crossed bobbins. If desired, the indications of the radiogoniometer may be rendered automatic, as by means of a servo-motor. Additional features involve insuring a proper sensitivity of the instrument at all azimuths, and correcting for errors caused by known local wave deviations, such as are introduced by the ship.

Other objects and advantages will be explained hereinafter and will be particularly pointed out in the appended claims, it being understood that it is intended, by suitable expression in the claims, to cover all the novelty that the invention may possess.

The nature and the objects of the inventions will be more fully explained in connection with the accompanying drawings,

in which Fig. 1 is a diagrammatic view of apparatus and circuits constructed and arranged according to a preferred embodiment of the present invention; Fig. 2 is a diagrammatic view illustrating a preferred coupling transformer; Fig. 3 is a diagrammatic view illustrating several methods of connecting the transformer into circuit; Fig. 4 is a similar view illustrating a preferred, automatic indicating means; Figs. 5 and 6 are diagrammatic views illustrative of preferred connections for insuring proper sensitivity at all azimuths; Fig. 7 is a diagrammatic view of a preferred mechanism intended to correct for errors, and Fig. 8 is a diagrammatic view combining the showings of Figs. 1 and 4 into a unitary system.

The coil aerials or loops may be of any suitable form, having well defined planes and having about the same pick-up area in these planes. A loop with a well defined plane of orientation may, for example, consist of a winding, equivalent to a plane coil, and having a suitable fixed surface or area and a fixed position. A receiving loop of this kind may have any desired shape, as circular or polygonal. Two or more windings with a well defined plane, connected in series, are also equivalent to a loop aerial of this sort.

The two receiving loop antennae 1 and 2 are diagrammatically shown in Figs. 1 and 8, fixed on the craft at an angle to each other, preferably a right angle, and connected in series with a common tuning condenser 3, but with a special feature without which they would be equivalent to only a single loop. This special feature is that the connections of one of the loops are periodically reversed with respect to the remainder of the circuit. This result may be brought about, for instance, by alternately reversing the sense or direction of the windings of one of the loops with respect to the other. In the illustrated embodiment of the invention, the ends 4, 5 of the windings of this loop are periodically exchanged, relatively to the ends 6, 7 of the remainder of the circuit, by means of a rotating commutator 8 having

two insulated sectors, contacting with brushes fixed to the supports 4, 5, 6 and 7. The commutator may be continuously rotated in any well known manner, as by means of a 5 motor, as hereinafter described. Care is taken to dispose the loop windings so that their mutual induction shall not be affected by the reversal, with the result that their total self induction shall remain the same during 10 the two reversals. The connections may be traced as follows: from a terminal 151 at one side of the condenser 3, through the loop 2, by way of a conductor 152, to the brushes 6 and 4; from the brush 4, by way of a conductor 154, through the loop 1, by way of a conductor 156, to the brushes 5 and 7; and from the brush 7, by way of a conductor 158, back to a terminal 160 at the other side of the condenser 3. It will be noted that when 15 the commutator 8 occupies a position at right angles to the illustrated position, it will connect the brushes 4 and 7 and the brushes 5 and 6, thus reversing the connections of the loop 1.

20 This wave-receiving circuit is connected, in any suitable manner, to the input circuit of a radio-frequency amplifier, shown as two vacuum tubes 170, though it will be understood that as many tubes as desired may be used. According to the illustrated embodiment of the invention, the connections to the input circuit of the amplifier 170 are effected by means of conductors 172 and 174, the former of which connects the terminal 25 151 with the filament, and the latter of which connects the terminal 160 with the grid of the first tube 170. The primary winding of the before-mentioned special transformer is connected, either directly or 30 indirectly, in the output circuit of the last tube 170. In the drawings, the amplifying and detecting tubes are shown as "triodes", but it is obvious that, without departing from the nature of this invention, they may 35 be replaced by other types of tube.

40 The combination of the two loop aerials 1 and 2, connected as illustrated and described, is equivalent, when the commutator occupies one of its positions, to a single loop aerial having a resultant plane coinciding with one of the planes bisecting the angle between the loops 1 and 2. When the commutator occupies its other position, and the connections of one of the loops become therefore 45 by reversed, the corresponding loop equivalent to the combination of the two loops 1 and 2 has a resultant plane coinciding with the other bisecting plane. The net effect of the successive reversals, therefore, is to yield 50 rapidly in succession two resultant, or phantom, loops respectively occupying planes at right angles to each other and corresponding to the planes that bisect the angles between the loops. The incoming signal waves are 55 thus periodically received as though they

were received by these two resultant loops disposed at right angles to each other. The waves thus induced in the loop aerials by the received waves are amplified without proportional change in intensity by the amplifying tubes, assuming that the tubes are operated on suitable portions of their characteristic curves, and are thus transmitted, without proportional change, to the transformer. 70

One of the transformer windings, primary or secondary, comprises two crossed winding parts or bobbins, which are disposed at the same angle to each other as the angle between the crossed, wave-energy-receiving loops 1 and 2. The other transformer winding, secondary or primary, comprises one or more windings that may be parallel geometrically, or in the same plane. Either of these transformer windings is fixed, and 80 the other is rotatable about an axis coinciding with a diameter of the winding. The winding parts 9 and 10, as also those indicated at 11 and 12, may be connected in 85 series, or parallel, as desired.

90 A preferred transformer is illustrated more particularly in Fig. 2, the two winding parts or bobbins that form between them a right angle, or any other suitable angle corresponding to that between the circuit 95 loops, being indicated at 9 and 10. The geometrically parallel winding parts are indicated at 11 and 12. According to the connections illustrated in Figs. 1 and 8, the crossed winding parts 9 and 10 form the 100 primary circuit and the parallel winding parts 11 and 12 form the secondary circuit.

105 The connections of one of the winding parts, preferably one of the crossed windings 9 or 10, are periodically reversed, like those of one of the loops, by means of a commutator 32, which may be of similar construction to the commutator 8 and that is shown in Fig. 8 on the same shaft with the commutator 8. The other windings, 110 preferably the parallel windings 11 and 12, are not reversed.

115 The connections may be traced as follows: from the plate of the last amplifier tube 170, by way of a conductor 176, to the primary winding part 9; thence, by way of a conductor 182, to the commutator 32. From the commutator 32, the circuit continues, by way of a conductor 186, to the primary winding part 10; thence, by way of a conductor 194, back to the commutator 32; and from the commutator 32, by way of a conductor 196, back to the filament of the last 120 amplifier tube 170. The winding parts 9 and 10 are thus shown in Figs. 1 and 8 connected in series as they pass through the commutator 32. When the commutator 32 occupies a position at right angles to that illustrated, the conductor 182 will be connected with the conductor 194, and the con- 125

ductor 186 with the conductor 196. In such a condenser 13; indifferently this may be directly or through the high voltage. 5

duct 186 with the conductor 196. In such a condenser 13; indifferently this may be directly or through the high voltage. 5

primary winding part, relative to the winding part 9, will be reversed. This will take place simultaneously with the reversal of the connections of the loop 1.

The result, as already described more at length in connection with the loop antennæ 1 and 2, is to provide the equivalent of two 10 transformer-winding parts, successively effective and perpendicularly disposed in the planes bisecting the planes between the winding parts 9 and 10. By making the 15 reversals of the transformer connections synchronous with those of the loop aerials, the reversed amplified currents will affect the transformer simultaneously with the reception of the emitted-waves by the loop aerials.

20 An amplifier is used between the loops and the transformer for the following reason: If the transformer was directly connected in the loop circuit, the impedance of the loops may be changed by the reversals 25 of the connections because of the change of mutual inductance between the loops and the transformer; thence the currents would not be proportional to the electromotive forces induced in the two reversed connections 30 of the loops, and proportionality is desirable for an accurate indication of direction.

With the loop aerials and the transformer operating in the manner above set forth, 35 with simultaneous reversal of the loops and the transformer windings, the direction, relatively to the receiving loops (and, therefore, to the craft on which they are fixed), of the emitting source or radio sending station 40 (to the radio signals of which the loop-aerial circuit is tuned), is obviously determined by that position of the movable part of the transformer windings relatively to the fixed part of the transformer windings, 45 for which the intensities of reception are equal for the two reversals. This equality can be observed by the pilot in any desired manner, as with the aid of a measuring instrument, or an electro-magnetic relay, as shown at 17, or by a telephone, with an 50 audible rate of reversals, as more particularly hereinafter described.

It will be readily understood that the result is the same if one of the parallel 55 winding parts, 11 or 12, is reversed, because the mutual induction of one of the couples 9, 11, or 10, 12 will change by this operation exactly as if one of the crossed winding parts were reversed. The output of the 60 transformer will thus be the same whether one of the crossed parts or one of the parallel parts is reversed.

It will be noted that the connection, by way of the conductor 196, back to the filament of the last amplifier tube 170 is through

70 The condenser 13, which is thus disposed in series with the primary transformer circuit, prevents the commutator 32 from affecting the direct plate current of the amplifier. It prevents also the possible formation of sparks at the commutator which sparks have a very bad effect on the amplifier as is well known. The whole is shunted by a choke coil or other impedance 14, across 75 which the plate circuit is connected, as will be understood by persons skilled in the art.

75 The primary bobbins, preferably the crossed bobbins 9 and 10, may be connected in the primary circuit in various ways, three such ways being illustrated in Fig. 3. The secondary winding parts are omitted from this Fig. 3, for clearness. The first example of Fig. 3 differs from that of Fig. 1 in 80 that the crossed winding parts 9 and 10 are electrically connected in parallel. In the second example, the winding parts 9 and 10 are apparently connected independently, but they are really connected in parallel through 85 their coupling with the plate circuit. The third example illustrates an indirect series connection of the windings. It will be understood that each winding part may be replaced by equivalent sets of other windings, in planes of orientation as defined for the aerial loops. Obviously, no change is 90 effected in the invention if the transformer is divided into several parts; for instance, if the separate parts enclosed in the dotted lines 15 and 16, Fig. 2, are separated. The two parts of the movable winding thus split up should, however, by any well known means, be caused to move together as a unit.

95 The secondary winding parts 11 and 12 of the transformer are connected in the input circuit of another amplifier, which may comprise vacuum tubes 244. The connections may be traced as follows: from the filament of the first tube 244 of the second amplifier, by way of a conductor 246, to the secondary winding part 11, thence, by way of a conductor 248, to the secondary winding part 12, and finally, by way of a conductor 252, to the grid of the said first 100 amplifier tube 244.

105 Energy from the output circuit of the second amplifier 244 is utilized to actuate an instrument for indicating the equality of the intensities of reception. To this end, the last tube 244 of the second amplifier may be used as a detector. If the instrument used is an electromagnetic, direct-current indicator, or a sensitive, polarized relay 17, the connections of the instrument 110 may be periodically reversed synchronously with the reversals of the loop aerials and of the transformer. In Figs. 1 and 8, the instrument 17 is shown associated with a Wheatstone bridge 266 in the plate circuit 115

of the last tube, but this is for illustrative purposes only, as other arrangements may equally well be used.

The connections are as follows: from the 5 plate of the detector tube 244 of the second amplifier, by way of a conductor 253, to a vertex 267 of a Wheatstone bridge 266; thence, by way of a conductor 254, to a commutator 256 shown on the same shaft with, 10 and operated in synchronism with, the commutators 8 and 32. From the commutator 256, the circuit continues, by way of a conductor 258, to an energizing coil 260 of the relay 17. Thereafter, the circuit continues, 15 by way of a conductor 261, back to the commutator 256; and from the commutator 256, by way of a conductor 262, to the opposite vertex 269 of the Wheatstone bridge 266; thence, through one of the arms of the 20 Wheatstone bridge 266, to a third vertex 271, and by way of a conductor 264, through a plate battery 265, and back to the filament of the last or detector tube 244 of the said second amplifier. The fourth vertex 271 of 25 the Wheatstone bridge is directly connected by a conductor 275 with the filament of the detector tube. It will be noted that the relay 17 is bridged, through the commutator 256, across the said two opposite vertices 267 and 269 of the Wheatstone bridge by conductors 254 and 262. The connections to the 30 relay 17 are thus reversed simultaneously with the reversal of the loop 1 and the primary winding part 10. The output circuit of the detector tube 244 of the second 35 amplifier, as before described, is connected with the transformer windings.

When the intensities of reception are equal for the two reversals of the reversible wind 40 parts, the indicator of the instrument 17 will occupy its zero or neutral or null position. This is because the commutator turns so rapidly that the inertia of the instrument will prevent the indicator from leaving its 45 zero position.

The angle corresponding to the direction of the sending station may obviously be read on a graduated or calibrated scale 328 by means of a movable pointer or other indicator 332 cooperating with the scale and carried on the axis 22 of the movable transformer winding; or, vice versa, by means of a fixed pointer and movable graduated scale. The indicator or index 332 may be fixed to 50 the axis 22, as illustrated in Figs. 4 and 8, or it may be loosely connected thereto for the purpose hereinafter explained in connection with Fig. 7.

Assuming that the radiogoniometer of the 60 present invention is used on an air craft to which the loops are fixed, all that the pilot has to do, in order to reach his destination, is so to steer his craft that the indicator of the instrument shall remain in its zero position. The craft will then make the required, 65

constant angle to the direction of the waves emitted from the sending station. This constant angle will be given on the scale 328 of the movable transformer winding.

To render the indications automatic, the 70 commutators for effecting the reversals should be continuously rotated by a suitable motor, as before stated. This instrument 17, being shown in Figs. 4 and 8 as a polarized, null-point indicating relay having two 75 contact members 336 and 338, will bear on one or the other of the two contact members according as the intensity of reception is stronger for the one or the other of the alternations on reverse of the connections. 80

According to the preferred embodiment of the invention that is herein illustrated and described, the indications are rendered automatic by causing one of the contact members, 85 by means of a servo-motor, to turn the movable winding in a given sense or direction, and the other contact member to turn it in the other sense. If the directions of rotation are so chosen that the intensities of reception, for the two reversals of the loop 1 90 and the transformer winding 10, shall have a tendency to become equal, the movable winding of the transformer will stop in the position at which these intensities are equal for the two reversals. The angle corresponding to this position corresponds to the 95 direction of the sending station. When the winding assumes this position, the relay 17 will occupy its zero or null position, and the motor will not be further actuated. 100

An arrangement for effecting automatic indication in accordance with a preferred embodiment of the present invention is diagrammatically illustrated in Figs. 4 and 8. The relay 17 actuates, by means of a two-grid vacuum tube 18, a second relay 19, 105 that is much more powerful than the relay 17, and which energizes an electric motor 20 so that its armature shall rotate in one direction or the other, according as the relay closes one contact member or the other. The motor 20 is energized from an independent power source S. The relay 19 bridges the plate and a grid of the two-grid tube 18 110 in such manner that the current flowing in the windings shall be about zero when the relay 17 occupies its zero position. The motor 20 is provided with a shaft 40 upon which is mounted a worm 126 meshing with a gear 125 that is fixed to the axial shaft 115 or arbor 22 of the rotatable winding, shown at 11, 12. The motor 20 thus rotates the movable winding 11, 12, in one direction or the other, according to which contact member, 120 336 or 338 is closed by the relay 17 until the relay 17 comes to rest in its neutral position. As before stated, the movable winding may be the winding 9, 10, in which event the other winding 11, 12 would be fixed. A magnetic 125

130

clutch 21 may be actuated along with the motor though this is not necessary.

If the connections between the relay 17 and the motor remain invariable, the movable winding will assume stable positions for reading only in the interval between two opposite quadrants. But such stability can readily be secured when passing from a stable quadrant to the following quadrant by reversing, during such passage, the direction of rotation of the motor 20 relative to the two contact members of the relay 17. This may be effected by exchanging the connections, either between the two contact members 336 and 338 of the relay, or between the two terminals of the armature circuit or the field circuit of the motor. This operation may, however, be carried out automatically by means of cams, mounted on the axis 22 of the movable winding and which may be caused to open and close the necessary contact members at the proper time.

The incoming or received waves will obviously be received with different intensities when coming from different directions. They may arrive from such a direction that the electromotive force induced in the wave-receiving aerial loops 1 and 2 is very feeble for one of the reversals. Under such conditions, the special transformer, equalizing the electromotive forces of the two reversals, will produce electromotive forces in its output that are feeble for both reversals. When the induced electromotive force in the aerial loops 1 and 2 is feeble for one of the reversals, therefore, detection is rendered very difficult. The apparatus will then be so very insensitive that the indications will not be accurate. If the loop aerials are then turned through a suitable angle, say 45° , the waves arriving along the least sensible directions will be received at a corresponding suitable angle, thus improving the operation of the device. If the loops only were turned, it would be necessary to add or subtract the said angle to the angle read on the graduated scale. This may, however, be avoided by turning the fixed winding of the transformer through the same angle, for the movable winding will then occupy the same position relatively to the scale before and after the rotation.

The loops and the transformer may, therefore, be made adjustable though, as before pointed out, the loops and the fixed winding of the transformer are maintained fixed during the signal-receiving operation. To effect this rotatable adjustment of the two planes of the loops and of the fixed part of the transformer 9, 10, 11, 12 through the desired angle, as an angle of 45° , any desired mechanism may be employed.

It is preferred, however, to effect the rotatable adjustment of the loops and of the

transformer winding electrically, rather than mechanically. To this end, the planes of eight individual loops (or equivalent windings) may preferably be symmetrically arranged around an axis O, as shown in Fig. 5, where the loops are diagrammatically represented and numbered I to VIII, inclusive. Although the planes of the loops are shown as being in the plane of the figure, for clearness, it must be understood that they are supposed to be in vertical planes and symmetrically disposed around the axis O. The windings will be considered as in two groups, first, I, II, III and IV; and second, V, VI, VII and VIII. In the first group, the windings of the loops I, II, III and IV are connected in series, the senses of the windings of the first two loops being the same, but opposite to those of the other two. In the second group, the windings of the other four loops V, VI, VII, VIII are also connected in series, but all in the same direction. Each of these groups is electrically equivalent to a single phantom loop aerial with a defined plane and the planes of the two equivalent phantom loops thus formed are angularly disposed, i. e. perpendicular. Should these two groups be connected together in series, and in series also with the tuning condenser, while periodically reversing the windings of one of the two groups, the assembly of these eight loops would alternately be equivalent to a fixed loop aerial and another loop aerial perpendicular thereto. The operation otherwise is the same as already described.

If we pass to a second and similar arrangement of connections, in which each loop is replaced by the next following or the next preceding loop, the results will be the same as if all the loops had been mechanically turned through an angle of 45° . All these loops, furthermore, will have remained symmetrically connected in the oscillating circuit formed by the loops and the condenser in series. Devices for automatically effecting these various connections, when the movable windings of the transformer 9, 10, 11, 12 occupy positions of weak sensibility, are within the province of persons skilled in the art. This may be accomplished, for instance, by cams mounted on the axis 22 of these windings, and operable to cause the opening and closing of a series of contact members connected to the ends of the loop windings.

In the system of contact members illustrated in Figure 5, however, only a switching by hand is indicated in order to avoid confusion in the drawings. In this figure the switching is indicated as being made by the set of blades M which may be thrown to the right or to the left to make the two connections mentioned above.

For a normal operation, the set of blades

M is positioned on the right as indicated in the figure. It may be readily seen by following the circuits, with this position of the blades, that the loops I, II, III, and IV are all connected in series, the loops I and II being connected in the opposite direction relatively to the loops III and IV; and the ends of the resultant loop thus formed are connected to the brush 6 and to the amplifier in the same manner as loop 2, of Figure 1, is connected to the same brush and amplifier. It may also be seen that with the same switching, the loops V, VI, VII, VIII, are connected in series, all in the same direction, and the terminals of the resultant phantom loop thus formed are connected to the brushes 4 and 5 in the same manner as the loop 1 is connected to the same brushes.

When the set of blades M is thrown to the left, it may be seen by following the circuits, that, by this second switching, each group of loops, VIII, I, II, III, and IV, V, VI, VII, are connected in series and the two resultant phantom loops thus formed are connected to the commutating ring 8 and to the amplifier in the same manner as loops 1 and 2 are connected, in Figs. 1 and 8, to the same commutating ring and amplifier.

If it is noticed that the loop VIII is now connected in a reversed direction relatively to the direction it had before, and also that the loop II had been reversed so as to have the same direction of winding as loop III, it is clear that by this second switching, the two systems of loops, I, II, III, IV, and V, VI, VII, VIII, of the first switching have been replaced respectively by the two systems of loops VIII, I, II, III, and IV, V, VI, VII with the same relative directions of the loops. Therefore, by passing from the first switching to the second switching, an operation has been performed which is equivalent to a mechanical rotation of the ensemble of the loops through an angle of 45° .

So much for the adjustment of the loops. To effect a corresponding electrical adjustment of the transformer, so as to produce the same effect as a 45° mechanical rotation, the windings 9 and 10 may each be divided into two equal parts $9a$, $9b$, $10a$, and $10b$, as shown in Fig. 5 and Fig. 6, where each winding is diagrammatically represented. For normal operation, the end b will be connected to the end c and the end f to the end g ; and the two windings thus formed will be connected in series while periodically reversing one or the other of them. When entering zones of weak sensibility, however, the end b will be connected to the end g , and the end f to the end d ; and the two windings thus formed will be connected in series, while periodically reversing the sense of one of them. The effect of this change of electrical connections is the same as if the

windings had been mechanically turned through an angle of 45° . This change of connections also may be effected in any well known way, as by cams and contact members, and at the same time as that of the loop aerials. 70

In the switching of the transformer illustrated in Fig. 35, however, only a switching by hand is indicated in order to avoid confusion in the drawings. As indicated in this figure, the switching is made by the set of blades N which may be thrown to the right or the left to make the change of connections. 75

For a normal operation the set of blades 80
N is positioned on the right. It may be
readily seen that, with this first switching,
the primary coils of the transformer are con-
nected to the commutating ring 32 and to
the amplifier in the same manner as the con-
nections of the transformer indicated in
Figs. 1 and 8. 85

With the second switching (with the set of blades N to the left), it may be easily seen, by following the circuits, that with the commutating ring in the position indicated in Fig. 5, the coils 9a and 9b, of winding 9, are in series in the same direction, while the coils 10a and 10b, of winding 10, are connected in series in reversed directions; therefore, the resultant flux of the winding 10 is nil, and the resultant phantom coil for this commutation is constituted by the real winding 9. When the commutator 32 is turned through a right angle, relatively to what is shown in Fig. 5, coils 9a and 9b are connected in reversed directions, and the coils 10a and 10b are connected in the same direction; therefore, with this commutation, the resultant flux of the winding 9 is nil, and the resultant phantom coil is constituted by the real winding 10. Then, with the two alternate commutations, made by the rotation of the commutator 32, the alternate resultant phantom coils are alternately coils 110

110
sultant phantom coils are alternately coils equivalent to the windings 9 and 10. These phantom coils with the switching just indicated (blades on the left) are at 45° relatively to the phantom coils of the first switching (with set of blades N to the right), since, as explained in relation to Figs. 1 and 8, the phantom coils in the latter case are at 45° relatively to the coils 9 and 10. Thus, by throwing the set of blades of switch N to the left, an operation equivalent to a mechanical rotation of the transformer coils through 45° is accomplished. 115
120

The switchings of the loops and of the transformer coils must be performed simultaneously in order to turn the resultant loops and resultant transformer winding through 45° simultaneously. Thus, as explained before, the inaccuracies which may arise from weak receptions are avoided. 125

It is desirable, upon occasion, to compensate. 130

sate for deviations of aberrations of the radio waves. These deviations may, or may not, be introduced by local causes. Among such are the deviations caused by the mass 5 of the craft. These deviations are not constant, but vary with the angular position occupied by the movable transformer winding. The values of the errors caused by the deviations for various azimuths or angular positions 10 of the movable transformer winding may be determined in advance, either experimentally, for each type of air plane, or by theoretical calculations. Such angle of correction may be allowed for, while still 15 directing the craft with reference to the signal waves emitted from the sending station, merely by adjusting the position of the index or other indicator 332 of the instrument; normally, as by manipulating an index 20 controlling button or the like, or automatically as presently to be described. The index 332 will be under the control of the movable winding of the transformer, as previously described, except that the index will 25 thus be manually or automatically adjusted through the desired angle. The air plane will, therefore, make the required, corrected angle, corresponding to the direction of the incoming waves.

According to the preferred embodiment of the invention that is herein illustrated and described, the necessary correction may be allowed for by adjustably mounting the index or other indicator 332 upon the axis 30 22 of the movable transformer winding, as illustrated in Fig. 7, from which the movable winding is omitted, for clearness. The indicator 332, shown as a needle, is here shown loosely mounted on the axis 22, instead of 35 being fixed thereto, as described in connection with Figs. 4 and 8, and it bears, as by means of a spring 23, against a cam 24. The shape of the cam 24 has been previously determined, experimentally or theoretically, 40 as before stated, so as automatically to correct for the necessary deviations, depending upon the angular position occupied by the movable transformer winding. The cam 24 is fixed to a pinion 25 that is geared to a 45 fixed pinion 26 centered upon the movable winding axis 22. The axis of the pinion 25 turns with the axis 22 as a unit. When the axis 22 is turned, therefore, the cam 24 turns also: first, bodily about the axis 22, 50 moving the needle with it, as before described, and without correction for errors; and, secondly, owing to the meshing engagement of the pinions 25 and 26, about the axis of the pinion 25, giving thus a relative or 55 correcting movement to the needle. The degree of this last-described movement of the needle is the required correction. Errors are thus automatically compensated for by 60 the cam 24, in accordance with the angular position occupied by the movable trans-

former winding if, as before stated, the cam has previously been properly designed.

As before stated, of course, the indicator needle 332 may be replaced by a movable graduated scale. It will also be understood that this correction may be made whether the apparatus is moved by the servo motor, or is under hand control.

The invention is not merely applicable to airplane and dirigible navigating, but it may be used anywhere, whether on land or at sea, and using any kind of craft, aerial, land or marine.

Other modifications, too, will occur to persons skilled in the art, and all such are considered to fall within the spirit and scope of the present invention, as defined in the appended claims.

What is claimed is:—

1. A radiogoniometer comprising two fixed loops disposed at an angle to each other and adapted to receive a signal from a radio-wave source, commutating means for reversing the sense of one of the loops, amplifying means for the currents induced in said loops, inductive coupling means connected with the amplifying means and upon which the amplified currents are impressed, said coupling means having a movable part for indicating directly the direction of the radio-wave source, a relay connected with said inductive coupling means so as to be operated thereby, a null-point indicator controlled in accordance with the actuation of said relay, and means controlled by the relay for actuating the movable part of the coupling means.

2. A radiogoniometric device having, in combination, a plurality of loops symmetrically disposed around an axis, means connecting the loops into circuit to provide a composite loop aerial pick-up arrangement equivalent to two resultant phantom loops having a constant angular disposition with respect to one another, means for relatively reversing the resultant phantom loops, and switching means for rotating the resultant phantom loops through an angle corresponding to the angle between the symmetrically disposed loops.

3. In a radiogoniometer, an amplifier having an output circuit, a transformer connected in the output circuit and having plurality of parts, one of the parts comprising crossed windings and the other part comprising one or more parallel windings, one of the parts being movable relatively to the other, and means for periodically reversing the connections of one of said crossed windings.

4. A radiogoniometer having, in combination, an amplifier having an output circuit, a transformer connected in said output circuit and having a primary winding and a secondary winding each having two parts,

- a capacity in series with the primary winding, and impedance in shunt to the primary winding, the parts of one of the windings being disposed at an angle to each other, and means for relatively reversing the connections of the parts of one of the windings.
5. In a radiogoniometer, an amplifier having an output circuit, a transformer having two parts forming respectively the primary and the secondary, the primary being connected in said output of the amplifier, one of the parts comprising crossed windings and the other part comprising one or more parallel windings, one of the parts being movable relatively to the other, means for periodically reversing the connections of one of said crossed windings, means for connecting the secondary of the transformer in the input circuit of an additional amplifier having an output circuit, a measuring instrument connected in the output circuit of the additional amplifier, and means for periodically reversing the connections of said measuring instrument in synchronism with said reversal of one of the crossed windings.
6. In a radiogoniometer, an amplifier having an output circuit, a transformer having two parts forming respectively the primary and the secondary, the primary being connected in said output circuit of the amplifier, one of the parts comprising crossed windings and the other part comprising one or more parallel windings, one of the parts being movable relatively to the other, means for periodically reversing the connections of one of said crossed windings, means for connecting the secondary of the transformer in the input circuit of an additional amplifier having an output circuit, a measuring instrument, means for periodically reversing the connections of said measuring instrument in synchronism with the reversal of one of the crossed windings, and a Wheatstone bridge connected in the said output circuit of the additional amplifier, the last tube of said additional amplifier being inserted in one arm of the bridge, the plate of said tube being connected to one of the vertices and the cathode to the other vertex of said arm, the other arms of the bridge being constituted by resistances, the said instrument being connected to said one vertex and to the opposite vertex, and the plate current source being connected to the other two remaining opposite vertices.
7. A radiogoniometer having, in combination, two fixed crossed loops for receiving a signal from a station, means connecting the loops in series, means for relatively reversing the connections of the loops periodically, an inductive coupling means connected with the output of the loops and having a movable part, and means controlled by the electromotive forces in the inductive coupling means for actuating said movable part to indicate the direction of the station.
8. A radiogoniometer having, in combination, two crossed loops, means for relatively reversing the connections of the loops periodically, an amplifier having an input circuit and an output circuit, the loops being connected with the input circuit, a transformer connected with the output circuit having a primary winding and a secondary winding each having two parts, a capacity in series with the primary winding, an impedance in shunt to the primary winding, the parts of one of the windings being disposed at an angle to each other corresponding to the angle between the crossed loops, and means for relatively reversing the connections of the parts of one of the windings in synchronism with the relative reversal of the connections of the loops.
9. A radiogoniometer having, in combination, two crossed loops for receiving a signal from a station and having an output circuit, means for relatively reversing the connections of the loops, a transformer having a primary winding and a secondary winding each having two parts, the parts of one of the windings being disposed at an angle to each other corresponding to the angle between the crossed loops, a motor and a circuit controlling the same, means connecting the primary winding in the output circuit of the loops and the secondary in the circuit controlling the motor, respectively, means for relatively reversing the connections of the parts of one of the windings synchronously with the relative reversal of the loops, the loops and one of the windings being fixed relative to the other winding, the motor being mechanically connected to said other winding, and means controlled by the signal for actuating said motor to adjust said other winding in accordance with the location of the station.
10. A radiogoniometer having, in combination, loops substantially symmetrically arranged around an axis, means connecting in series a group of the loops to form a resultant phantom loop, means connecting in series another group of the loops to form another resultant phantom loop angularly disposed relatively to the first named resultant phantom loop, means connecting the groups in series, means for relatively reversing periodically the connections of the resultant loops, and switching means for turning the two resultant phantom loops through an angle corresponding to the angle between the symmetrically disposed loops.
11. A transformer having a primary winding and a secondary winding, one of the windings being divided into a plurality of symmetrically disposed parts, means connecting the parts into two circuits, means connecting said two circuits in series, means

for periodically reversing the connection of one of said two circuits to provide two alternate angularly disposed resultant phantom coils, and switching means for turning the 5 resultant phantom coils through a predetermined angle.

12. In an apparatus for use on a craft having an inductive coupling means with a movable part adjusted to a position corresponding to a desired angular relation of the craft relatively to the direction of a radio transmitting station, the method of indicating on a null-point indicator the deviation of the craft from said desired angular 10 relation, comprising receiving two component parts of the radiant energy, alternately reversing one of the said component parts whereby two alternate resultant components are formed, resolving said two resultant 15 components into two alternate electromotive forces in the inductive coupling means, and utilizing the deviation from equality of said electromotive forces for actuating the null-point indicator.

20 13. Apparatus of the character described having, in combination, a winding movable about an axis, an indicator controlled thereby, an error-correcting cam for controlling the indicator, the cam having a double movement of rotation about its own axis and the axis of the winding, and means controlled by the movement of the winding for controlling the position of the cam.

25 14. A radiogoniometer which comprises two equivalent loops fixed with respect to each other, the loops being arranged in series relation and having an output circuit, the windings of said loops being electrically reversible with respect to each other, means 30 for reversing the windings, means connected in the output circuit of the loops for amplifying the received signals, the amplifying means having an output circuit, a transformer connected in the output circuit of 35 the amplifying means and upon which said amplified signals are impressed and having windings movable with respect to each other, a null-point instrument, connections for the instrument, means for moving said transformer windings relative to each other until they register equal current deviations on the 40 instrument for each alternation of the current through said loops, means for reversing the instrument connections, and means for 45 detecting the signals from the transformer and impressing them on said instrument.

50 15. A radiogoniometer having, in combination, two crossed loops, means for relatively reversing the connections of the loops, a transformer having two windings each having two parts, the parts of one of the windings being disposed at an angle to each other corresponding to the angle between the crossed loops, means for relatively reversing the connections of the parts of one 55

of the windings synchronously with the relative reversal of the loops, means connecting one of the windings with the loops, the loop and one of the windings being fixed relative to the other winding.

70

16. A radiogoniometer having, in combination, two crossed loops having an output circuit, means for relatively reversing the connections of the loops periodically, a transformer having a primary winding and a secondary winding each having two parts, the parts of one of the windings being disposed at an angle to each other corresponding to the angle between the crossed loops; means for relatively reversing the connections of the parts of one of the windings in synchronism with the relative reversal of the connections of the loops, means connecting the primary winding in the output circuit of the loops, the loops and one of the windings being fixed relative to the other winding, and means for relatively moving the said other winding to a position so as to impress on said secondary winding equal electromotive forces for the two reversed 80 connections.

85

17. A radiogoniometer having, in combination, two crossed loops having an output circuit for receiving a signal from a station, means for relatively reversing the connections of the loops periodically, a transformer having a primary winding and a secondary winding each having two parts, the parts of one of the windings being disposed at an angle to each other corresponding to the angle between the crossed loops, means for relatively reversing the connections of the parts of one of the windings in synchronism with the relative reversal of the connections of the loops, a relay, means connecting the primary winding in the output circuit of the loops and the secondary winding to the relay, the loops and one of the windings being fixed relative to the other winding, and means controlled by the relay for relatively moving the said other winding in accordance with the location of the station.

95

18. A radiogoniometer having, in combination, two crossed loops having an output circuit for receiving a signal from a station, means for relatively reversing the connections of the loops periodically, a transformer having a primary winding and a secondary winding each having two parts, the parts of one of the windings being disposed at an angle to each other corresponding to the angle between the crossed loops, means for relatively reversing the connections of the parts of one of the windings in synchronism with the relative reversal of the connections of the loops, a Wheatstone bridge, means connecting the primary winding in the output circuit of the loops and the secondary winding with two vertices of one arm of the Wheatstone bridge, the other 100 110 115 120 125 130 .

- arms of the bridge being constituted by resistances, a relay, means connecting the relay with one of said two vertices and the opposite vertex of the Wheatstone bridge, the 5 loops and one of the windings being fixed relative to the other winding, and means controlled by the relay for relatively moving the said other winding in accordance with the location of the station.
- 10 19. A radiogoniometer having, in combination, two crossed loops having an output circuit for receiving a signal from a station, means for relatively reversing the connections of the loops, a transformer having a 15 primary winding and a secondary winding each having two parts, the parts of one of the windings being disposed at an angle to each other corresponding to the angle between the crossed loops, means for relatively reversing the connections of the parts of one of the windings, a relay, means connecting the primary winding in the output circuit of the loops and the secondary winding with the relay, the loops and one of 20 the windings being fixed relative to the other winding, and means controlled by the relay for relatively moving the said other winding in accordance with the location of the station, the transformer being calibrated to indicate the direction of the station when the relay is in its neutral position.
- 25 20. A radiogoniometer having, in combination, a plurality of loops symmetrically arranged around an axis and having an output circuit, means connecting the loops as a composite loop aerial pickup arrangement equivalent to two resultant phantom loops having a constant angular disposition with 30 respect to one another, a transformer having a primary winding connected in the output circuit of the loops and a secondary winding, one of the windings being divided in a plurality of parts, means connecting the parts 35 of the divided winding into a circuit equivalent to a resultant phantom coil, and means for varying the connections of the loops and of the parts of the divided winding of the transformer to effect electrically a rotation 40 of the resultant phantom loops and of the resultant phantom coils through the same angle.
- 45 21. A radiogoniometer having, in combination, loops substantially symmetrically arranged around an axis and having an output circuit, means connecting in series a group of loops to form a resultant phantom loop, means connecting in series another group of the loops in another resultant phantom loop angularly disposed relatively to the first named phantom loop, means connecting the groups in series, means for relatively reversing periodically the connections of the groups, a transformer having a primary 50 winding and a secondary winding, the primary winding being connected in the output circuit of the loops, one of the windings being divided into a plurality of symmetrically disposed parts, means connecting the parts into two circuits, means connecting said two circuits in series, means for periodically reversing the connection of one of said circuits in synchronism with the reversal of the connections of the loops to provide two alternate angularly disposed resultant phantom coils, and switching means for turning the resultant phantom loops and the resultant phantom coils through the same angle.
- 55 22. A radiogoniometer having, in combination, two crossed loops for receiving a signal from a station, means for relatively reversing the connections of the loops, a transformer having two windings each having two parts, the parts of one of the windings being disposed at an angle to each other corresponding to the angle between the crossed loops, means for relatively reversing the connections of the parts of one of the windings synchronously with the relative reversal of the connections of the loops, means connecting one of the windings with the loops, the loops and one of the windings being fixed relative to the other winding, means for relatively moving the said other winding, the windings being calibrated, an indicator movable synchronously with the said relative movement of the windings and cooperating with the calibrations of the calibrated transformer for indicating the location of the station, an error-correcting cam for correcting the indications of the indicator, and means controlled in accordance with the said relative movement of the said other winding for controlling the operation of the cam.
- 60 23. A radiogoniometer having, in combination, two crossed loops for receiving a signal from a station and having an output circuit, means for connecting the loops in series, means for relatively reversing alternately the connections of the loops, inductive coupling means connected with the output circuit of the loops and having a movable part for indicating the direction of the station, and means for observing the equality of the electromotive forces induced in the said movable part during the two alternate relatively reversed connections of the loops.
- 65 24. A radiogoniometer having, in combination, two crossed loops for receiving a signal from a station, means for connecting the loops in series, means for relatively reversing alternately the connections of the loops, means for equalizing the two alternate outputs of the loops comprising a transformer connected with the loops and upon which the signals are impressed and having windings movable with respect to each other, and means for indicating the equality of the equalized outputs comprising a null-point

instrument, connections for the instrument, and means for moving said transformer windings relative to each other until they register equal current deviations on the instrument for each alternation of the current through said loops.

25. A radiogoniometer having, in combination, two crossed loops for receiving a signal from a station, means connecting the loops in series, means for relatively reversing the connections of the loops periodically, and inductive coupling means having a movable part adjustable to receive equal electromotive forces during the two alternate relatively reversed connections of the loops for a desired directional relation between the loops and the station.

26. An apparatus of the character described having, in combination, a craft, two crossed fixed loops on the craft for receiving a signal from a station, means connecting the loops in series, means for relatively reversing the connections of the loops periodically, inductive coupling means having a movable part adjustable to receive equal electromotive forces during the two reversed connections of the loops for a desired angular relation between an axis of the craft and the direction of the station, and means controlled by the said movable part for indicating the deviations of the said axis of the craft from said angular relation.

27. The method of indicating the direction of a radio transmitting station by an inductive coupling means having a movable part, which comprises receiving two directional component parts of the radiant energy from said transmitting station, one of said component parts being alternately re-

ceived in reversed directions whereby two alternate angularly disposed resultant components are received, resolving said two resultant components into two alternate electromotive forces in the inductive coupling means, and utilizing the deviation from equality of said two electromotive forces for actuating said movable part of the inductive coupling means to indicate the direction of the station.

28. The method of indicating the direction of a radio transmitting station by means of an inductive coupling means having primary and secondary windings one of the windings being movable, which comprises receiving two directional component parts of the radiant energy from said transmitting station one of said component parts being alternately received in reversed direction whereby two alternate angularly disposed resultant components are received, resolving each of said resultant components into two subsequent directional components in the primary of the inductive coupling means, reversing one of said subsequent directional components synchronously with said reversed receptions of one of the component parts of the radiant energy whereby two subsequent alternate resultant components are formed in the inductive coupling means, resolving said two subsequent resultant components into two alternate electromotive forces in the secondary of the inductive coupling means, and utilizing the deviation from equality of said two electromotive forces for actuating the direction indicating means.
